SLEEPING BAG

Norman E. Phillips and Peter K. Faerber,
Washington, D. C.

Application February 9, 1938, Serial No. 189,680

1 Claim. (Cl. 5—343)

The present invention relates to sleeping bags.

An important object of the invention is to provide a sleeping bag which will possess the maximum warmth for the weight of the bag.

5 A further object of the invention is to provide a bag having oppositely arranged sides, both of which sides are filled with heat insulating material, and are uniform in thickness throughout substantially their entire areas.

10 A further object of the invention is to provide a sleeping bag which is water repellent to a considerable extent and yet will permit of some degree of ventilation through its walls.

15 A further object of the invention is to provide means for connecting the opposite edges of the free end of one side of the bag, for contracting the bag laterally about the neck and chest of the user and produce a portion of double thickness, and for connecting the opposite edges of the free 20 end of the other side of the bag for providing a hood.

25 A further object of the invention is to provide a sleeping bag which may be made in companion side sections of simplified design, embodying straight lines, thus reducing the cost of production.

Other objects and advantages of the invention will be apparent during the course of the following description.

30 In the accompanying drawing forming a part of this application and in which like numerals are employed to designate like parts throughout the same,

Figure 1 is a perspective view of a sleeping bag 35 embodying our invention, showing the same unoccupied by the user.

Figure 2 is a similar view, with parts of the bag arranged as when occupied by the user.

Figure 3 is a transverse section taken on line 40 3—3 of Figure 1, and,

Figure 4 is a fragmentary transverse section taken on line 4—4 of Figure 2.

In the drawing, wherein for the purpose of illustration is shown a preferred embodiment of 45 our invention, the numerals 5 and 6 designate companion oppositely arranged side members, which coincide throughout the major portion of their length, Figure 1, when the side members are arranged in a flat superposed relation with 50 the side members 6 longer than the side member 5, and the free end of the member 6 projecting longitudinally beyond member 5, for a substantial distance, as shown. Each side member has oppositely arranged longitudinal edges 7 and 8, 55 which are preferably parallel. The side mem-

bers 5 and 6 have transverse end edges 9, arranged at a right angle to the edges 7 and 8 and free transverse edges 10 and 11, also arranged at a right angle to the edges 7 and 8. The side members 5 and 6 have diagonal side edges 12, converging toward the closed end edges 9, with respect to the side edges 7. The closed end of the bag therefore has one side tapered, as the user ordinarily bends the legs to some extent, in sleeping. The present bag is shown as intended for use by one sleeping upon the right side, and the bag may also be constructed by placing the diagonal edges 12 upon the opposite edges of the bag, for sleeping on the left side.

Each side member 5 and 6 comprising a casing including outer and inner walls or sheets 13 and 14, and an intermediate wall 15. The outer and inner walls 13 and 14 are made of a flexible fabric which is water repellent, to a considerable extent and also down proof. This fabric is closely woven and is relatively stout, and is dipped in a water proofing solution to render it water repellent, but the fabric is not coated with a continuous film as is the case with rubber dam. While this fabric is water repellent and down proof, it is not air tight as one may breathe through it. This is highly desirable as it provides for a suitable degree of ventilation for the entire bag. The wall or divider 15 is fabric and may be formed of muslin or the like. In the construction of each side member, the divider 15 is attached to the outer wall 13 by spaced longitudinal rows of stitches 16, and the divider 15 is also secured to the inner wall 14 by spaced longitudinal rows of stitches 17. The stitches 17 are staggered with respect to the stitches 16 whereby the divider 15 forms with the outer and inner walls 13 and 14 alternately arranged longitudinal pockets 18 and 19. These pockets 18 and 19 are 30 triangular in cross section and face or taper in opposite directions. The pockets are filled with flexible and compressible heat insulating material 19' such as down, or feathers, or a mixture of the two. By the alternate arrangement of the triangular pockets 18 and 19, with the apex of one pocket facing toward the base of the other pocket, when these pockets are filled with the down or the like, the pockets serve to hold the down from undue movement and provide a side 35 member which is of uniform thickness substantially throughout its entire area, thus affording the maximum heat and comfort for the weight of the bag.

In the formation of the side members 5 and 6, 40 55

In the formation of the side members 5 and 6, 55

the outer and inner walls 13 and 14 and the divider 15 are stitched together throughout their marginal edges as shown at 20, the stitching extending about the longitudinal edges 7, 8 and 5 12, and the closed end edge 9. The longitudinal pockets are then filled with the down or the like and the free transverse edges 10 and 11 are stitched together, as shown at 21. The side member 5 may then be arranged upon the side member 6, and these side members 5 and 6 10 stitched together throughout their marginal edges, extending from a point 22 to a point 23, as shown at 24.

The points 22 and 23 being spaced inwardly 15 a substantial distance from the free edge 10, and the side member 5 is provided with a chest flap 25, which may be regarded as having a length extending from the points 22 and 23 to the free edge 10. This flap is integral with the side member 5 and is free from connection with the side member 6. The chest flap 25 is provided at one end with a socket 26, suitably secured thereto and at its opposite end with a stud 27, also suitably secured thereto. The stud and socket 20 extend upon the opposite surfaces of the side member 5, before the flap 25 is folded, and the stud and socket constitutes a snap fastener, of the ordinary type used upon gloves or the like.

The side member 6 extends longitudinally 30 beyond the flap 25 and beyond the points 22 and 23 for forming a hood flap 28, considerably longer than the flap 25. The hood flap 28 is separate from the flap 25, forming slits 29 therewith. Attached to one end of the flap 28 is a socket 30, 35 and a stud 31, extending to the opposite sides of the flap 28. The stud 30 and socket 31 constitutes a snap fastener such as are used upon gloves or the like.

In the use of the bag, the same may be laid 40 upon the floor or the like and will assume the position shown in Figure 1. The user may crawl into the open end of the bag at the edges 10 and 11 and after suitably arranging himself therein, the ends of the chest flap 25 are folded inwardly and such ends are connected by the socket 26 and stud 27. This causes the free end of the bag to somewhat taper to conform generally to 45 the contour of the shoulders. The folding of the chest flap 25 provides a chest protecting portion 50 of double thickness throughout the major portion of its area which covers the chest. The head now projects beyond this chest portion and the free ends of the hood flap are folded forwardly

and inwardly to surround the head and chest portion with the head within the hood portion, which is now tubular. The outer end of the tubular hood portion is open and the head may be moved entirely within the hood portion or partly out of the same, to suit the convenience 5 of the user.

It is to be understood that the form of our invention herewith shown and described is to be taken as a preferred example of the same and that various changes in the shape, size, and arrangement of parts, may be resorted to, without departing from the spirit of our invention or the scope of the subjoined claim.

Having thus described our invention, we claim: 15

A sleeping bag comprising, oppositely arranged sides which are attached together at their longitudinal edges and at one end edge only for forming a bag which is closed at one end and open at the opposite end, one side extending longitudinally for a substantial distance beyond its edge attachments to afford a chest flap which extends beyond the open end of the bag, said chest flap being continuous throughout substantially its entire area and free from a central 25 opening, the other side extending longitudinally for a substantial distance beyond its longitudinal edge attachments and beyond the free end of the chest flap for providing a hood flap, the chest flap and the hood flap when the bag is empty 30 and the flaps are lying substantially flat, overlapping each other and providing arm receiving passages at the longitudinal edges of the bag, which passages are inwardly of the free end of the chest flap, fastening elements attached to the 35 hood flap near its free end and near its longitudinal edges, the arrangement of the fastening elements being such that the hood may be folded about the head by passing the arms through the arm receiving passages and the fastening elements secured together, and fastening elements secured to the chest flap near its free end and near its longitudinal edges, the chest flap being foldable over itself in a direction inwardly from the arm receiving passages, the fastening 40 elements of the chest flap being adapted to be secured together by the hand or hands of the user within the bag, the folding of the chest flap providing a double thickness for the chest flap throughout a considerable extent of its area. 50
